United States Patent Office

Des. 218,490
Patented Aug. 18, 1970

218,490

MAILBOX

Charles E. Blumberg, 1933 Red Oak Drive,
Adelphi, Md. 20783

Filed Feb. 12, 1969, Ser. No. 15,754

Term of patent 14 years

Int. Cl. D31

U.S. Cl. D74—9

FIG. 1

FIG. 2

FIG. 3

FIG. 4

FIG. 5

FIG. 6

FIG. 1 is a front perspective view of a mailbox embodying my new design:

FIG. 2 is a front view of the mailbox shown in FIG. 1;

FIG. 3 is a left side view thereof, the side opposite thereto being similar in appearance;

FIG. 4 is a top view;

FIG. 5 is a rear view; and

FIG. 6 is a bottom view thereof.

I claim:

The ornamental design for a mailbox, as shown and described.
